[57] CLAIM

The ornamental design for a ground connector strap, as shown and described.

DESCRIPTION

FIG. 1 is a top perspective view of a ground connector strap showing my new design;

FIG. 2 is a top plan view thereof;

FIG. 3 is a side elevational view thereof, the opposite side being substantially a mirror image;

FIG. 4 is a bottom plan view thereof;

FIG. 5 is a left end elevational view thereof; and

FIG. 6 is a right end elevational view thereof.
